SPINDLE AND BOBBIN

Filed Jan. 23, 1925

UNITED STATES PATENT OFFICE.

WILLIAM BESWICK, OF SACO, MAINE, ASSIGNOR TO SACO-LOWELL SHOPS, OF BOSTON, MASSACHUSETTS, A CORPORATION OF MASSACHUSETTS.

SPINDLE AND BOBBIN.

Application filed January 23, 1925. Serial No. 4,226.

This invention relates to spindles and bobbins of the type used in textile machinery, especially in spinning and twisting frames.

It is an important object of the invention 5 to devise a spindle and bobbin construction in which the bobbin will be positively driven and will be held securely in its running position while, at the same time, being readily removable from the spindle or replaceable 10 thereon while the spindle is running at normal speed. It has been attempted heretofore to secure these advantages in the clutch type of spindle. Spindles of this type are, however, open to the objection that they 15 are relatively complicated in construction and therefore expensive to manufacture, and they necessarily involve small parts which are liable to get out of order and result either in failure to hold the bobbin or in causing 20 the bobbin to rotate eccentrically. The present invention provides a construction which affords the advantages of the clutch type of spindle while avoiding its objectionable features.

25 In using the present spindle and bobbin construction it is found that after a short time there is considerable variation in the level of the bobbins in a given spinning frame. The same ring rail controls the feed 30 of the yarn or thread to all of these bobbins and the traverse of this rail must, therefore, be adjusted for the worst condition. In other words, the upper limit of movement of the rail must be set for the lowest bobbin, 35 while the lower limit of traverse must be adjusted for the highest bobbin. This is objectionable not only in reducing the height of the thread bodies on the bobbins but also in locating the feeler bunches, which 40 are initially wound on the bases of the bobbins, at different elevations. That is, it is customary in beginning the filling of a bobbin to wind a small bunch of yarn on the base of the bobbin for subsequent engagement 45 with the feeler mechanism in the loom. It is important for the proper operation of this feeler mechanism that these bunches of yarn shall be wound in substantially the same position on all the bobbins. It is an 50 object of this invention, therefore, to devise a construction of spindle and bobbin which will ensure the support of the bobbins at substantially the same level in a spinning or twisting frame and thus eliminate the difficulties just described.

The nature of the invention will be readily understood from the following description when read in connection with the accompanying drawings, and the novel features will be particularly pointed out in the appended claims.

Referring now to the drawings,

Figure 1 is a perspective view of a spindle with a bobbin thereon;

Fig. 2 is a vertical, cross sectional view of 65 the spindle and bobbin shown in Fig. 1;

Fig. 3 is a perspective view of the sleeve portion of the whirl and the cooperating portion of the bobbin;

Fig. 4 is a vertical cross sectional view of 70 the parts shown in Fig. 3, showing them in their cooperative relationship to each other; and

Figs. 5 and 6 are perspective, cross sectional views of the parts shown in Fig. 4, 75 showing them in different relationships to each other.

The construction shown comprises a spindle 2 which may be of the usual form. Frictionally secured on this spindle is a whirl 80 3 which includes a pulley section 4 and a sleeve portion 5, the latter portion projecting upwardly from the main body of the whirl. The sleeve is tapered at a somewhat smaller angle than the corresponding portion 85 of whirls of the usual type.

Formed in the upper part of the sleeve 5 are several grooves 6. Each of these grooves is of very short circumferential length and extends from the peripheral surface of the 90 sleeve inwardly and upwardly to the upper surface thereof, opening into the top surface of the sleeve at a point close to the spindle. Each groove is very sharply inclined. It will be obvious from an inspection of the 95 drawings that the lower wall 7 of each groove is very abrupt or flat, while the upper wall 8 is gradually inclined, this inclination providing a portion 9 which is outwardly bulged and overhangs the bed or bottom of 100 the groove.

The bobbin shown comprises a wooden body 10 which may be of the usual form. Set into the base of this bobbin is a cylindrical sheet metal bushing 12 having a plurality of lugs 13 struck inwardly from the upper part thereof, the number of these lugs being equal to the number of grooves 6. This bushing may be made of brass or steel 105 and, if made of steel, may be hardened.

When this bobbin is placed on the spindle it will automatically center itself by the engagement of the bushing 12 with the tapered sleeve 5. The lugs 13 will strike the shoulders 7 and, guided on these shoulders, will turn the bobbin relatively to the spindle as the bobbin descends, the lugs thus passing under the bulged portions 9 of the upper walls of the grooves. The downward movement of the bobbin is stopped by its contact with the upper horizontal surface 14 of the whirl body 3. Assuming that the spindle is rotating, the bobbin now will be positively driven by the engagement of a portion of the wall 8 of each groove with the lug 13 which rests in that particular groove. The spindle rotates in a clockwise direction, Figs. 5 and 6, and consequently the overhanging portion 9 of the upper wall of each groove acts on the lug 13 in that groove to force the lug downwardly in much the same way that the threads of a screw would operate on a follower or nut engaged by the screw. When, therefore, the bobbin is simply dropped on the running spindle, it is forced down into its operative relationship to the spindle by the action of the walls of the grooves 6 on the lugs 13. The inclined upper walls 8 of the grooves also prevent the bobbin from being accidentally lifted off its seat on the whirl by the traverse of the thread, or for any other reason. That is, the action of the grooves on the lugs, as just described, holds the bobbin down and effectually prevents it from rising accidentally.

When it is desired to doff the bobbin it is simply necessary to grasp it and lift it, this movement resulting in relatively turning the bobbin and spindle far enough to disengage the lugs 13 from the bulged or overhanging portions 9 of the grooves. Due to the fact that the grooves are very steeply inclined, a very slight turning movement only is required to release the lugs from the grooves. This will be evident from an inspection of Figs. 4, 5 and 6, in which Figs. 4 and 6 show the lugs 13 in their running positions in the grooves 6. It will be observed that it is impossible to lift the bobbin off the spindle simply by a movement parallel to the spindle, due to the fact that the parts 9 overlie the lug 13. When the bobbin is rotated slightly in a clockwise direction, however, or the spindle 2 is rotated slightly in the opposite direction, the lug 13 is then released from the shoulder 9, as shown in Fig. 5, and the bobbin may be slipped off the spindle.

In this construction the height of the bobbin relatively to the spindle preferably is fixed by virtue of the fact that the bobbin rests on the seat or surface 14, and in fact is held against this seat by the action of the grooves 6 on the lugs 13. This construction, therefore, effectually avoids the variation in level of the bobbins which has been a trou-

blesome factor in prior constructions. The taper of the sleeve 5 is made very slight and the lower end of the bushing 12 fits the portion of the spindle which it engages when the bobbin is seated on the surface 14. In this construction the taper simply serves to center the bushing, all the driving being done by the action of the walls of the grooves on the lugs 13. It is not necessary, therefore, to make the sleeve 5 tapered, but it can be made cylindrical in form and the bushing 12 made to slide freely on the part 5 without having excessive looseness.

Preferably the base of the bobbin is internally bevelled, as shown at 15, Fig. 4. This construction provides ample space at the base of the sleeve 5 to receive the threads which accumulate on this portion of the whirl. A considerable quantity of "stripping" thread can accumulate on the sleeve before it is necessary to remove it.

It will now be appreciated that this invention provides a construction which has all the advantages of the clutch type of spindle, while at the same time avoiding its objectionable features. The bobbin can be put on the spindle or doffed while the spindle is running, the bobbin goes on without chatter and is securely held in its operative position on the spindle. At the same time the construction is very simple, can be manufactured economically, and is not liable to get out of order.

While I have herein shown and described the best embodiment of my invention that I have so far devised, it is contemplated that the invention may be embodied in other forms without departing from the spirit or scope thereof. For example, the grooved end of the sleeve 5 can be made in a separate piece and forced on to the spindle, this construction having the advantage of permitting the grooved piece to be hardened.

Also, I have shown the sleeve 5 provided with four grooves 6, but this number, and the number of lugs, can be varied as found expedient. Each lug and groove operates exactly like the other, and while a plurality of lugs and grooves are preferable, still it is within the scope of the invention to use a single lug on the bobbin bushing and a single groove on the whirl sleeve. I do not desire, therefore, to be limited to the details of the construction shown, although I prefer to use substantially the construction shown in the drawings. Obviously this feature can be used independently of the shoulder 14 if it should be desired to eliminate the latter and depend on the tapered sleeve to stop the downward movement of the bobbin.

It will also be evident that the groove and lug construction of the sleeve 5 and bushing 12 might be reversed, the grooves being formed in the bushing, and the lugs on the sleeve. This, however, will be an obvious

reversal of the parts and therefore would be within the scope of the present invention.

As above stated, the spindle shown in the drawings is designed to run in a clockwise direction, which is the more common practice. In adapting this invention to spindles that run in a counter-clockwise direction, it is simply necessary to cut the grooves 6 in a direction oppositely inclined to that of the grooves shown in the drawings, as will be evident, and to direct the lugs 13 opposite to those shown in the drawings so that they will cooperate with the grooves in the same manner and produce the same results as described above.

The terms "spindle" and "bobbin" as used in this specification and in the claims are intended to designate spindles and bobbins of the type used in textile machinery.

Having thus described my invention, what I desire to claim as new is:

1. The combination of a spindle and a bobbin, said spindle and bobbin having cooperating parts serving to utilize the rotary motion of the spindle to draw the bobbin positively downward on the spindle into its driving relationship thereto when the bobbin is dropped on the running spindle, but permitting the bobbin to be freed from the running spindle by an upward pull on the bobbin.

2. The combination of a spindle, a whirl mounted on said spindle, and a sleeve projecting upwardly from said whirl, said sleeve having a steeply inclined groove extending downwardly from the top thereof but extending circumferentially thereof for a short distance only.

3. The combination of a spindle, a whirl mounted on said spindle, a sleeve projecting upwardly from said whirl and having one or more steeply inclined grooves extending from the peripheral surface of the sleeve inwardly and upwardly to the upper surface of the sleeve, the upper wall of each groove being cut away to provide an inclined sur-

face overhanging the bottom of the groove.

4. The combination of a spindle, a whirl fast on said spindle, a sleeve projecting upwardly from said whirl, a bobbin having a base portion constructed to fit on said sleeve and having a plurality of internal lugs, said sleeve having a plurality of shoulders running at a steep incline from the peripheral surface thereof inwardly and upwardly to the top of the sleeve, each of said shoulders being adapted to support and guide one of said lugs, and the metal of said sleeve above each shoulder being shaped to form a bulge to overlie a lug resting on said shoulder and prevent the movement of the lug upwardly in a direction parallel to the spindle.

5. The combination of a spindle, a whirl mounted on said spindle, a sleeve projecting upwardly from said whirl and having one or more steeply inclined grooves extending from the peripheral surface of the sleeve inwardly and upwardly to the upper surface of the sleeve, each of said grooves having an abrupt lower wall and a gradually inclined upper wall with a portion of said upper wall overlying the bottom of the groove.

6. The combination of a spindle, a whirl mounted on said spindle, a sleeve projecting upwardly from said whirl, a bobbin having a metal bushing in the base portion thereof to fit on said sleeve, and cooperating parts on said bobbin and bushing for utilizing the rotary motion of the spindle to draw said bushing and bobbin downwardly on said sleeve.

7. The combination of a spindle, a whirl mounted on said spindle, a sleeve projecting upwardly from the upper surface of said whirl, and a bobbin mounted on said spindle, said bobbin and sleeve having parts cooperating to utilize the rotary motion of the spindle to draw said bobbin downwardly and thereby to hold the base of said bobbin against the top face of said whirl.

WILLIAM BESWICK.
